UNITED STATES PATENT OFFICE.

ELI BROTHERS, OF LYNN, MASSACHUSETTS, ASSIGNOR TO UNITED SHOE MACHINERY CORPORATION, OF PATERSON, NEW JERSEY, A CORPORATION OF NEW JERSEY.

UPPER-PULLING MACHINE.

1,289,634.

Specification of Letters Patent. Patented Dec. 31, 1918.

Application filed July 24, 1918. Serial No. 246,521.

To all whom it may concern:

Be it known that I, ELI BROTHERS, a citizen of the United States, residing at Lynn, in the county of Essex, and State of Massachusetts, have invented certain Improvements in Upper-Pulling Machines, of which the following description, in connection with the accompanying drawings, is a specification, like reference characters on the drawings indicating like parts in the several figures.

This invention relates to upper pulling machines for use in the manufacture of boots and shoes, this application being a continuation of my earlier application Serial No. 46,662, filed on August 21, 1915 in so far as the claims cover subject-matter disclosed in the earlier application. The invention is herein shown as embodied in a machine particularly designed for pulling an upper preliminarily to stretch it and draw it into approximate conformity to the contour of a last prior to the presentation of the shoe to a pulling-over machine. It will be understood, however, that in its broader aspects the invention is not limited in its applicability to machines for thus performing a preliminary upper pulling operation but is of general applicability to machines for pulling uppers on lasts.

Under some conditions in the manufacture of boots and shoes, as for example where the upper of the shoe is so cut that it is comparatively small for the last or where the last is shaped in a peculiar manner, the best results require that the upper be pulled to some extent before the shoe is subjected to the customary pulling-over operation in order to locate the margin of the upper in a more convenient position for engagement by the pulling-over grippers or to improve the final shape of the shoe. By seizing the upper at the toe end of the last and pulling it lengthwise of the last the margin of the upper at the toe, if the upper is cut short, may be so located as to permit the toe gripper of the pulling-over machine readily to engage it when the shoe is presented to that machine, and such a preliminary lengthwise pull upon the upper also insures better results in the final shaping of the upper about the heel end portion of the last. Similarly, by seizing and pulling the upper at the opposite sides of the forepart, the margin may be more conveniently located for presen-

tation to the pulling-over side grippers, and by thus drawing the upper down to the wood of the last back of the toe prior to the final pulling-over operation at the toe and the sides a better final shaping of the forepart of the upper is insured.

An object of this invention is to provide an improved machine for use in pulling uppers on lasts, the machine shown as an illustrative embodiment of the invention having characteristics which contribute effectively to improved results in pulling an upper as a preliminary operation prior to the final pulling-over operation.

A feature of the invention consists in a novel combination of means for use in pulling an upper both longitudinally and transversely, including a toe gripper and means responsive to pressure of the work for causing it to close upon the upper. In the construction shown the toe gripper is closed when the work is presented to the machine by pressure of the shoe upon a shoe rest which serves also as a fulcrum about which the shoe may be swung to tension the upper longitudinally before it is pulled transversely, the construction also permitting the shoe to be swung subsequently to change the longitudinal tension in proportion to the tension applied transversely.

Further features of the invention are to be recognized in a novel combination of means for causing a gripper to close upon an upper in response to pressure of the work and means for effecting relative movement of the gripper and the last to pull the upper; in novel means for holding a gripper closed during the upper pulling operation; in novel means affording relief to the pull of a gripper in the event of excessive tension; and in various details of construction and combinations of parts, all of which will now be described with reference to the accompanying drawings and pointed out in the claims.

In the drawings,

Figure 1 is a view in side elevation of a machine in which the invention is embodied, portions of the mechanism being broken away to show the interior construction, and

Fig. 2 is a front elevation of the machine, with portions shown in vertical section.

The machine comprises a frame 2 having a horizontal portion 4 adapted, in the construction shown, to be secured to a work

2
 bench and serving to support a plurality of upwardly projecting grippers arranged respectively to engage an upper at the toe end and at the opposite sides of the forepart of a last. The toe gripper comprises a substantially fixed jaw 8 mounted upon the upper end of a rod 10 slideable vertically in a casing 12 within limits determined by a stop screw 14, and a jaw 16 pivoted at 18 to the 5
 10 jaw 8 and normally maintained in an open position by means of a spring 20 which is connected at one end to the pivoted jaw and at its other end to a pin 22 secured to the rod 10 and movable in a slot 24 in the casing 12.
 15 A spring 26 bearing at one end on the frame and at its other end on a collar 28 on the rod 10 tends to hold the toe gripper in its lowermost position determined by engagement of a flange 30 with the upper end of the casing 20 12, while permitting the gripper to rise under certain conditions as will be herein-after explained. The casing 12 is provided with a horizontally flanged portion 32 movable in guideways in the frame to permit the 25 toe gripper to be adjusted for shoes of different lengths, a clamping screw 34 being provided to hold the gripper in adjusted position. For effecting closure of the gripper jaws the pivoted jaw 16 is provided with a forwardly extending arm 36 formed at its 30 front end to provide upwardly extending fingers 38 for engagement with the bottom of a shoe substantially at the ball of the shoe. By downward pressure of the shoe 35 the arm 36 may thus be operated against the tension of the spring 20 to cause the pivoted jaw 16 to close upon the margin of the upper when the shoe is presented to the machine, and by depressing the rear portion of the shoe thus resting upon the members 38 the 40 operator is enabled to swing the shoe in a direction to cause the upper to be pulled longitudinally by the toe gripper while the jaw 16 is held in its closed position by downward pressure of the shoe.
 45 The two opposite side grippers comprise upright gripper casings 40 having horizontally flanged portions 42 movable in guideways 44 of the frame for adjustment of the side grippers for different widths of shoes, the grippers being held in adjusted position by means of clamping screws 46. Secured at the upper end of each of the casings 40 is a fixed gripper jaw 48, and pivoted on the 50 casing is a coöperating jaw 50 having a tail portion arranged to be engaged by a roll 52 mounted on a closing bar 54 which is vertically slideable in the casing 40 and extends downwardly below the horizontal portion 45 of the frame. A spring 56 mounted in a vertical slot in the bar 54 and bearing at its lower end against a transverse portion of the bar and at its upper end against a pin 58 on the casing 40 tends to move the closing 60 bar 54 downwardly and thus to swing the
 pivoted jaw 50 toward the other jaw to grip the upper. At its lower end the jaw 54 carries a roll 60 mounted in an elongated slot in a lever 62 which is pivoted on the frame, and below the lever 62 is pivoted a lever 64 70 having at its upper end a roll 66 arranged to engage the lower side of the lever 62 and thus to hold the lever 62 in an elevated position with the closing bar 54 raised against the tension of the spring 56 to permit the 75 gripper jaws to open in the normal position of rest indicated in Fig. 2. In order to control the closing of the side grippers and to maintain the lever 64 normally in its position indicated in Fig. 2, the machine is provided with a rod 68 vertically movable in a bearing 70 at the lower end of the frame and in a corresponding bearing in the horizontal portion 4 of the frame, this rod carrying a controlling member 72 which is arranged to 80 engage the lower arm of the lever 64 for elevating the lever 62 and the gripper closing rod, this member having a roll 74 at each side to eliminate excessive friction in the movement of the respective levers 64 by the 85 operation of the member. A spring 76 mounted on the rod 68 and bearing at its upper end against the frame and at its lower end on the member 72 tends to position the rod normally at its lower limit of movement 90 determined by engagement of the member 72 with the bearing 70. For elevating the rod 68 against the tension of the spring 76 the machine is provided with a treadle 78 pivoted at 80 on a base casting. At its upper 100 end face the rod 68 is roughened to serve as a shoe rest, the rod being arranged to engage the bottom of the shoe at the forepart and to elevate the shoe relatively to the grippers. In the normal position of the parts the 105 upper end face of the rod is located at some distance below the shoe, as shown in Figs. 1 and 2, thus permitting the toe gripper to be closed and the shoe to be swung in a direction for pulling the upper longitudinally 110 without interference by the rod. This arrangement of the parts, moreover, affords provision for the closing of the side grippers upon the upper prior to any substantial elevation of the shoe by the operation of the 115 shoe rest, it being understood that the side grippers are permitted to close through the action of the closing springs 56 when the controlling member 72 has been raised a sufficient distance to release the levers 64. 120 After the side grippers have been thus permitted to close, a further movement of the rod by raising the shoe causes the upper to be pulled transversely by the action of these 125 grippers and it may be also further pulled longitudinally by the action of the toe gripper.
 In order still to hold the toe gripper closed upon the upper when the shoe is raised by the rod 68 and is thus elevated relative 130

- tively to the fingers 38, the machine is provided with a rack 82 vertically slidable in a bearing in the frame, the teeth of this rack engaging a pinion 84 which is mounted in 5 fixed bearings and at its opposite side engages teeth which are cut in the rod 68. Slidably mounted in the rack member 82 is a rod 86 connected by a flexible chain 88 to the arm 36 of the pivoted gripper jaw 16 and carrying at its lower end a spring 90 which rests upon a nut 92 and when the parts are positioned as shown in Fig. 1, is maintained with its upper end spaced below the lower end of the rack member 82 to permit the 10 arm 36 to swing freely for closing or opening the gripper jaws unaffected by the spring 90. It will be evident, by reference to Fig. 1, that when the rod 68 is raised to cause the side gripper jaws to close upon the upper the 15 rack member 82 will be moved downwardly, and will arrive in position to engage the spring 90 substantially at the time when the upper end of the rod 68 comes into engagement with the shoe. As the rod 68 continues 20 to rise and to elevate the shoe, further downward movement of the rack member 82 serves to compress the spring 90, the tension of which is sufficient to overcome the tension of the gripper opening spring 20, and 25 thus through the rod 86 and the chain 88 to hold the toe gripper jaws closed on the upper with pressure increasing in proportion to the extent of upward movement of the shoe.
- 30 35 In the operation of the machine, briefly summarized, the operator presents a shoe to the machine by inserting the toe end portion of the upper in the open toe gripper jaws and then by downward pressure of the 40 shoe upon the fingers 38 causes the gripper to close upon the upper. By swinging the shoe about the fingers 38 as a fulcrum the operator is then enabled to cause the upper to be pulled longitudinally by the action of the toe gripper to any extent desired in order to bring the margin into more convenient location for engagement by the pulling-over toe gripper and also in order to set the 45 upper about the heel end portion of the last. While holding the shoe with the upper in its longitudinally pulled condition, the operator then depresses the treadle 78 and elevates the shoe rest rod 68, thus causing the 50 side grippers to close upon the upper and then raising the last relatively to both the side grippers and the toe gripper, the toe gripper being held in its closed position upon the upper by the action of the rack and pinion mechanism hereinbefore described. In this manner the upper is pulled across the 55 last to bring the margin into more convenient location for engagement by the pulling-over side grippers and also is drawn down to the top of the last back of the toe, and in the same manner the upper may be further ten-
- sioned longitudinally by the action of the toe gripper. During the operation of the treadle, however, the operator is enabled, by swinging the shoe about the upper end of the rod 68 as a fulcrum, either to increase or to relax the longitudinal tension relatively to the transverse tension, the construction also permitting the operator to swing the shoe laterally in order to effect a relative adjustment between the upper and the last or between the last and the toe gripper. In the event of any undue strain upon the upper longitudinally, the spring 26 may yield, and thus permit the toe gripper to rise bodily to relieve the tension. After the upper has been pulled to the desired extent both longitudinally and transversely, the operator places his hand upon the shoe in position to retain the upper substantially in its pulled condition, and then releases the treadle 78 to permit the parts of the machine to return to their starting positions, the grippers opening to release the shoe. While holding the shoe in this manner the operator will then present it to a pulling-over machine to cause the upper to be pulled over and fastened in the usual way.
- It will be evident that the use of the machine herein shown permits uppers to be cut comparatively small for the last without detriment to the quality of the work and thus results in an important saving of upper stock.
- Having described the invention, what I claim as new and desire to secure by Letters Patent of the United States is,—
1. An upper pulling machine having, in combination, a gripper for engaging an upper at the toe end of a last, means responsive to pressure of the work to cause said gripper to close upon the upper, said means being constructed to serve as a rest about which the last may be swung for pulling the upper longitudinally, and means constructed and arranged for use subsequently to such swinging movement of the last to pull the upper transversely after it has been pulled longitudinally.
  2. An upper pulling machine having, in combination, a gripper for engaging an upper at the toe end of a last, means responsive to pressure of the work to cause said gripper to close upon the upper, said means being constructed to serve as a rest about which the last may be swung for pulling the upper longitudinally, and additional means for pulling the upper transversely.
  3. An upper pulling machine having, in combination, a gripper for engaging an upper at the toe end of a last, shoe engaging means constructed and arranged to cause said gripper to close upon the upper in response to pressure of the work and to cause the upper to be pulled longitudinally by said gripper in response to pressure of the oper-

- ator's hand upon the shoe, side grippers, and means for effecting relative movement of the last and the side grippers to pull the upper transversely.
5. An upper pulling machine having, in combination, a gripper for engaging an upper at the toe end of a last, means arranged to be engaged by the work to cause said gripper to close upon the upper, said means being constructed to permit the last to be fulcrumed upon it to cause the upper to be pulled longitudinally, side grippers, and means for effecting relative movement of the last and the side grippers to pull the upper transversely.
10. A machine for pulling an upper on a last having, in combination, a toe gripper, side grippers, means responsive to pressure of the work to cause the toe gripper to close upon the upper, said means being constructed to serve as a rest about which the last may be swung for pulling the upper longitudinally, and means for causing the side grippers to close upon the upper and for moving the last relatively to said grippers for pulling the upper transversely. 75
15. A machine for pulling an upper on a last having, in combination, a toe gripper, side grippers, means responsive to pressure of the work to cause the toe gripper to close upon the upper, said means being constructed to serve as a rest about which the last may be swung for pulling the upper longitudinally before it is pulled transversely, and means for causing the side grippers to close upon the upper and for moving the last relatively to the several grippers for pulling the upper both transversely and longitudinally. 80
20. A machine for pulling an upper on a last having, in combination, a toe gripper, side grippers, means responsive to pressure of the work to cause the toe gripper to close upon the upper, said means being constructed to serve as a shoe rest about which the last may be swung for pulling the upper longitudinally, a second shoe rest, and means for causing the side grippers to close upon the upper and for moving said second rest to cause the upper to be pulled by the grippers. 85
25. A machine for pulling an upper on a last having, in combination, a toe gripper, side grippers, means responsive to pressure of the work to cause the toe gripper to close upon the upper, said means being constructed to serve as a shoe rest about which the last may be swung for pulling the upper longitudinally, a second shoe rest, and means for causing the side grippers to close upon the upper and for moving said second rest to cause the upper to be pulled by the grippers. 90
30. Apparatus for pulling an upper on a last having, in combination, a base, a lower gripping jaw supported in fixed position by the base, an upper jaw movable toward the fixed jaw and having an operating arm extending at a substantial angle to the gripping face of the upper jaw and upon which a shoe can be rested to effect closing of the jaws and which is formed to permit the last that is within the shoe to be fulcrumed thereon to pull the upper lengthwise between the jaws and the last, and means for engaging the upper at the opposite sides of the last and pulling it transversely. 95
35. A machine for pulling an upper on a last having, in combination, a toe gripper comprising a rigid jaw, a movable jaw, and means projecting from said movable jaw for engagement with a shoe to cause the gripper to close in response to pressure of the shoe, side grippers arranged to engage the upper at opposite sides of the ball of a shoe presented to said toe gripper, and means to operate the side grippers. 100
40. A machine for pulling an upper on a last having, in combination, a toe gripper comprising a rigid jaw, a movable jaw, and means for causing closure of the jaws and stretching of the upper longitudinally in response to pressure of the shoe, side grippers arranged to engage the upper at opposite sides of the ball of a shoe presented to said toe gripper, and means to move the side grippers and the shoe last relatively for stretching the upper transversely. 105
45. A machine for pulling an upper on a last having, in combination, a toe gripper comprising a rigid jaw, a movable jaw, and means for causing closure of the jaws and stretching of the upper longitudinally in response to pressure of the shoe, side grippers arranged to engage the upper at opposite sides of the ball of a shoe presented to said toe gripper, and means to move the side grippers and the shoe last relatively for stretching the upper transversely. 110
50. A machine for pulling an upper on a last having, in combination, a toe gripper comprising a rigid jaw, a movable jaw, and means for causing closure of the jaws and stretching of the upper longitudinally in response to pressure of the shoe, side grippers arranged to engage the upper at opposite sides of the ball of a shoe presented to said toe gripper, and means to move the side grippers and the shoe last relatively for stretching the upper transversely. 115
55. A machine for pulling an upper on a last having, in combination, a toe gripper comprising a rigid jaw, a movable jaw, and means for causing closure of the jaws and stretching of the upper longitudinally in response to pressure of the shoe, side grippers arranged to engage the upper at opposite sides of the ball of a shoe presented to said toe gripper, and means to move the side grippers and the shoe last relatively for stretching the upper transversely. 120
60. A machine for pulling an upper on a last having, in combination, a toe gripper comprising a rigid jaw, a movable jaw, and means for causing closure of the jaws and stretching of the upper longitudinally in response to pressure of the shoe, side grippers arranged to engage the upper at opposite sides of the ball of a shoe presented to said toe gripper, and means to move the side grippers and the shoe last relatively for stretching the upper transversely. 125
65. A machine for pulling an upper on a last having, in combination, a toe gripper comprising a rigid jaw, a movable jaw, and means for causing closure of the jaws and stretching of the upper longitudinally in response to pressure of the shoe, side grippers arranged to engage the upper at opposite sides of the ball of a shoe presented to said toe gripper, and means to move the side grippers and the shoe last relatively for stretching the upper transversely. 130

- upon the upper, and means for causing the side grippers to close upon the upper and for effecting relative movement of all the grippers and the last to pull the upper.
- 5 15. An upper pulling machine having, in combination, grippers for engaging an upper at opposite sides of a last, a shoe rest, means for operating said shoe rest to move the last relatively to said grippers, mechanism responsive to movement of said operating means for causing said grippers to close upon the upper, a toe gripper, and means independent of said shoe rest operating means for causing the toe gripper to close upon the upper before the side grippers close.
- 10 16. An upper pulling machine having, in combination, grippers for engaging an upper at opposite sides of a last, a shoe rest, treadle operated means for causing said grippers to close upon the upper and for moving said shoe rest relatively to the grippers to pull the upper, a toe gripper, and means responsive to pressure of the work to cause said toe gripper to close upon the upper before the side grippers close.
- 15 17. In an upper pulling machine, the combination with a toe gripper and side grippers, of means comprising a pivoted shoe rest member responsive to pressure of the work to cause the toe gripper to close upon the upper, and treadle operated means for causing the side grippers to close upon the upper.
- 20 18. In an upper pulling machine, the combination with a gripper for engaging an upper at the toe end of a last, of means extending from one of the jaws of said gripper to be engaged and moved by the work for closing said jaw upon the upper, and means for effecting relative movement of the last and said gripper to pull the upper.
- 25 19. In an upper pulling machine, the combination with a gripper for engaging an upper at the toe end of a last, of means responsive to pressure of the work to cause said gripper to close upon the upper, and means for moving the last relatively to said gripper to pull the upper while the gripper is held substantially stationary.
- 30 20. An upper pulling machine having, in combination, an upright jaw, a companion jaw pivoted thereto and having an angular arm arranged to be engaged and rocked by the bottom of a shoe presented with the edge of the upper between the jaws, and last raising means arranged to engage the shoe bottom between said jaws and the shoe engaging end of said arm.
- 35 21. An upper pulling machine having, in combination, a rigid jaw, a movable jaw, means for causing closure of the jaws arranged to be operated by the shoe, a shoe rest, and means for operating the shoe rest to move the shoe substantially perpendicu-
- larly to its sole face and relatively to the jaws to stretch the upper between the last and the jaws while the jaws are held substantially stationary.
- 40 22. In an upper pulling machine, a gripper arranged to engage an upper on a last and comprising relatively movable jaws, means extending from one of said jaws into position to engage the bottom of a shoe and constructed to move said jaw to closed position in response to pressure of the shoe, and means for effecting relative movement of the gripper and the last to pull the upper.
- 45 23. In an upper pulling machine, the combination with a gripper for engaging an upper at the toe end of a last, of an arm extending from one of the jaws of said gripper into position to engage the bottom of the shoe and responsive to pressure of the shoe to close said jaws upon the upper, a shoe bottom rest, and means for operating said bottom rest to cause the upper to be pulled by the gripper.
- 50 24. In an upper pulling machine, the combination with a gripper for engaging an upper at the toe end of a last, of means responsive to pressure of the shoe to cause said gripper to close upon the upper, said means being constructed to serve as a rest about which the last may be swung for pulling the upper longitudinally, and means for effecting relative movement of the last and said gripper for further pulling the upper.
- 55 25. In an upper pulling machine, the combination with a gripper for engaging an upper at the toe end of a last, of means responsive to pressure of the shoe to cause said gripper to close upon the upper, said means being constructed to serve as a rest about which the last may be swung for pulling the upper longitudinally, and means constructed to engage the bottom of the shoe and to move the last relatively to said gripper for further pulling the upper.
- 60 26. In an upper pulling machine, the combination with a gripper for engaging an upper at the toe end of a last, of means responsive to pressure of the work to cause said gripper to close upon the upper, means for effecting relative movement of the last and said gripper to pull the upper, and means for holding the gripper closed during the upper pulling operation.
- 65 27. In an upper pulling machine, the combination with a gripper for engaging an upper on a last, of means for causing said gripper to close upon the upper, means for moving the last relatively to the gripper in a direction to pull the upper while the gripper remains substantially stationary, and additional means connected to the gripper to hold it closed during said movement of the last, said additional means being constructed and arranged to be rendered operative in consequence of the movement of the last.

28. In an upper pulling machine, the combination with a gripper for engaging an upper on a last, of means extending from said gripper into position to be engaged by the bottom of the shoe and responsive to pressure of the shoe to close the gripper on the upper, a shoe rest, means for operating said shoe rest to move the last relatively to the gripper for pulling the upper, and means for holding the gripper closed during the operation of the shoe rest.

29. In an upper pulling machine, the combination with a gripper for engaging an upper on a last, of means extending from said gripper into position to be engaged by the bottom of the shoe and responsive to pressure of the shoe to close the gripper on the upper, a shoe rest, means for operating said shoe rest to move the last relatively to the gripper for pulling the upper, and means connected to said shoe rest operating means for operating upon said gripper to hold it closed.

30. In an upper pulling machine, the combination with a gripper for engaging an upper on a last, of means extending from said gripper into position to be engaged by the bottom of the shoe and responsive to pressure of the shoe to close the gripper on the upper, a shoe rest, means for operating said shoe rest to move the last relatively to the gripper for pulling the upper, and a yielding connection between said shoe rest operating means and the gripper for holding the gripper closed.

31. In an upper pulling machine, the combination with a gripper for engaging an upper on a last, of means extending from said gripper into position to be engaged by the bottom of the shoe and responsive to pressure of the shoe to close the gripper on the upper, a shoe rest, means for operating said shoe rest to move the last relatively to the gripper for pulling the upper, and means constructed and arranged for operation in determined relation to the movement of the shoe rest to bring yielding pressure to bear upon said gripper to hold it closed.

32. In an upper pulling machine, a gripper for engaging an upper at the toe end of a last comprising a pair of jaws one of which is pivoted to swing toward and from the other, an arm extending from said pivoted jaw into position to be engaged by the bottom of a shoe for closing said jaw upon the upper, means for effecting relative movement of the last and said gripper to pull the upper, and means connected to said arm for holding the gripper closed during the upper pulling operation.

33. In an upper pulling machine, a gripper for engaging an upper at the toe end of a last comprising a pair of jaws one of which is pivoted to swing toward and from the other, an arm extending from said pivoted

oted jaw into position to be engaged by the bottom of a shoe for closing said jaw upon the upper, a shoe bottom rest, means for operating said rest to cause the upper to be pulled by the gripper, and a connection between said arm and rest for bringing yielding pressure to bear upon said pivoted jaw to hold the gripper closed.

34. In an upper pulling machine, a gripper for engaging an upper at the toe end of a last comprising a pair of jaws one of which is pivoted to swing toward and from the other, an arm extending from said pivoted jaw into position to be engaged by the bottom of a shoe for closing said jaw upon the upper, a shoe bottom rest, means for operating said rest to cause the upper to be pulled by the gripper, and means connected to said arm for holding the gripper closed with pressure increasing in proportion to the extent of the movement of the bottom rest.

35. In an upper pulling machine, the combination with a gripper for engaging an upper at the toe end of a last, of means responsive to pressure of the shoe for closing said gripper upon the upper, means for effecting relative movement of the gripper and the last to pull the upper, and means for holding said gripper closed with pressure increasing in proportion to the strength of the pull upon the upper.

36. In an upper pulling machine, the combination with a gripper for engaging an upper at the toe end of a last, of means responsive to pressure of the shoe for closing said gripper upon the upper, said means being constructed to serve as a rest about which the last may be swung for pulling the upper longitudinally, means for effecting relative movement of the gripper and the last for further pulling the upper, and means for holding said gripper closed during said further pull upon the upper.

37. In an upper pulling machine, the combination with a gripper for engaging an upper at the toe end of a last, of means responsive to pressure of the shoe for closing said gripper upon the upper, said means being constructed to serve as a rest about which the last may be swung for pulling the upper longitudinally, a shoe bottom rest, means for operating said bottom rest to cause the upper to be further pulled by the gripper, and means operative in determined relation to the movement of said bottom rest for operating upon said gripper to hold it closed.

38. In an upper pulling machine, a gripper for engaging an upper at the toe end of a last, said gripper comprising jaws one of which is pivoted to swing toward and from the other jaw, an arm connected to said pivoted jaw and extending into position to be engaged by the bottom of the shoe for clos-

- ing said jaw upon the upper, said arm being constructed to serve as a rest above which the last may be swung for causing the gripper to pull the upper while the gripper is held in closed position by the shoe, treadle operated means for moving the last relatively to said gripper for further pulling the upper, and a connection between said treadle operated means and said pivoted jaw for holding said jaw in closed position during said further pull upon the upper.
39. In an upper pulling machine, the combination with a gripper for engaging an upper at the toe end of a last, of means responsive to pressure of the shoe for closing said gripper upon the upper, grippers for engaging the upper at opposite sides of the last, means for effecting relative movement of the last and the side grippers to pull the upper transversely, and means for holding said toe gripper closed during the upper pulling operation.
40. In an upper pulling machine, the combination with a gripper for engaging an upper at the toe end of a last, of means arranged to engage the bottom of the shoe and responsive to pressure of the shoe for closing said gripper upon the upper, grippers for engaging the upper at opposite sides of the last, a shoe bottom rest, means for operating said bottom rest to cause the upper to be pulled transversely by the side grippers, and means connected to said toe gripper for holding it closed during the upper pulling operation.
41. In an upper pulling machine, the combination with a gripper for engaging an upper at the toe end of a last, of a member extending from said gripper into position to be engaged by the bottom of the shoe for closing said gripper upon the upper, a shoe bottom rest, side grippers, means for operating said bottom rest to move the last away from said closing member and cause the upper to be pulled by the grippers, and means connected to said member for holding the toe gripper closed during said movement of the last.
42. In an upper pulling machine, the combination with a toe gripper and side grippers, of means responsive to pressure of the shoe for closing said toe gripper upon the upper, said means being constructed to serve as a rest about which the last may be swung for pulling the upper longitudinally prior to the transverse pull of the side grippers, a shoe bottom rest, means for operating said bottom rest to cause the upper to be pulled transversely, and means for holding said toe gripper closed upon the upper during said transverse pull.
43. In an upper pulling machine, a gripper for engaging an upper at the toe end of a last, said gripper comprising a pair of jaws one of which is pivoted to swing to-
- ward and from the other, an arm connected to said pivoted jaw and arranged to be operated by pressure of the shoe for closing said jaw upon the upper and also to serve as a rest about which the last may be swung for pulling the upper longitudinally, grippers for engaging the upper at opposite sides of the last, a shoe bottom rest, means for operating said bottom rest to cause the upper to be pulled transversely by the side grippers, and connections between said operating means and said arm for holding the toe gripper closed during said transverse pull upon the upper.
44. In an upper pulling machine, a gripper for engaging an upper at the toe end of a last, said gripper comprising a pair of jaws one of which is pivoted to swing toward and from the other, an arm connected to said pivoted jaw arranged to be operated by pressure of the shoe for closing said jaw upon the upper and also to serve as a rest about which the last may be swung for pulling the upper longitudinally, grippers for engaging the upper at opposite sides of the last, a shoe bottom rest, means for operating said bottom rest to cause the upper to be pulled transversely by the side grippers, and a connection to said pivoted jaw for holding it closed upon the upper with pressure increasing in proportion to the extent of movement of the shoe rest.
45. An upper pulling machine having, in combination, grippers for engaging an upper at the toe and at opposite sides of a last, means responsive to pressure of the shoe for causing said toe gripper to close upon the upper, said means being constructed to serve as a rest about which the last may be swung for pulling the upper longitudinally prior to the transverse pull, means for moving the last relatively to the grippers to cause the upper to be pulled transversely by the side grippers, means for holding said toe gripper closed during said movement of the last, and means permitting said toe gripper to yield in response to the pull of the upper.
46. An upper pulling machine having, in combination, grippers for engaging an upper at the toe and at opposite sides of a last, means constructed to close said toe gripper upon the upper, said means being constructed also to serve as a rest about which the last may be swung by the operator for pulling the upper longitudinally while free from transverse tension, means for moving the last relatively to the side grippers to pull the upper transversely while the toe gripper retains its hold upon the upper, and means permitting the toe gripper to yield in response to the pull of the upper during said movement of the last.
47. In an upper pulling machine, a gripper for engaging an upper at the toe end

of a last, means responsive to pressure of the shoe for causing said gripper to close upon the upper, means for moving the last relatively to said gripper to pull the upper, and means permitting said gripper to yield to the pull of the upper when a predetermined tension is exceeded.

48. In an upper pulling machine, a gripper for engaging an upper at the toe end of a last, means arranged to engage the bottom of a last, means responsive to pressure of the shoe for closing said gripper upon the upper, said means being constructed to serve as a rest about which the last may be swung for pulling the upper, means for moving the last relatively to said gripper for further pulling the upper, and means permitting said gripper to yield during said further pull when a predetermined tension is exceeded.

49. In an upper pulling machine, a gripper for engaging an upper on a last, said gripper comprising a pair of jaws one of which is pivoted to swing toward and from the other, an arm extending from said pivoted jaw into position to be engaged by the bottom of a shoe for closing said jaw upon the upper, means for moving the last relatively to said gripper to pull the upper,

means connected to said pivoted jaw to hold it closed during said movement of the last, and means permitting said gripper to yield in response to the pull of the upper when a predetermined tension is exceeded.

50. An upper pulling machine having, in combination, a rigid jaw, a movable jaw, means for causing closure of the jaws arranged to be operated by the shoe, yielding supporting means for the jaws constructed to hold them substantially stationary during the upper pulling operation while permitting them to yield when a definite strain is exceeded, and means for moving the last relatively to the jaws to stretch the upper to an extent determined by the resistance of the yielding supporting means.

51. In an upper pulling machine, a gripper, a shoe rest, means for operating said shoe rest to cause the upper to be pulled by the gripper, and means constructed to maintain said gripper in a substantially stationary position during the upper pulling operation while permitting it to move yielding with the upper when a definite strain is exceeded.

In testimony whereof I have signed my name to this specification.

ELI BROTHERS.
